ALBERT HALL, OF NEW YORK, N. Y.

BUTTON-ATTACHING MACHINE.

SPECIFICATION forming part of Letters Patent No. 738,435, dated September 8, 1903.

Application filed February 23, 1901. Serial No. 48,609. (No model.)

To all whom it may concern:

Be it known that I, ALBERT HALL, a citizen of the United States, and a resident of the city of New York, borough of the Bronx, in the county of New York and State of New York, have invented certain new and useful Improvements in Button-Attaching Machines, of which the following is a specification.

The object of my invention is to provide a new and improved machine for attaching pronged metal buttons to articles of wearing-apparel, which machine is simple in construction, strong and durable, and fastens the buttons firmly and securely without breaking or 15 distorting the buttons or injuring the fabric.

In the accompanying drawings, in which like letters of reference indicate like parts in all the figures, Figure 1 is a side elevation of my improved machine for attaching buttons. Fig. 2 is a front elevation of the same. Fig. 3 is a sectional view on the line 3 3 of Fig. 1. Fig. 4 is an enlarged vertical sectional view through the button-guide and plunger-guide. Fig. 5 is a rear elevation of the plunger-guide, 25 parts being shown in vertical sectional view on the line 5 5 of Fig. 4. Fig. 6 is a detail vertical sectional view of the plunger and button-supporting plate. Fig. 7 is a side view, partly in section, of the button-supporting 30 plate and mechanism. Fig. 8 is a horizontal sectional view on the line 8 8 of Fig. 4. Fig. 9 is an enlarged sectional elevation of the button-guide, showing the escapement-slide. Fig. 10 is a sectional view on the line 10 10 of 35 Fig. 5, showing the escapement-slide. Fig. 11 is a sectional view on line 11 11 of Fig. 3.

The entire mechanism is supported by a standard A, secured to a suitable base-plate A', and this standard is provided with a horizontally-projecting arm B, the free end of which carries the anvil C, upon which the fabric a is rested, whereon the button is to be secured. The anvil C consists of a central stem C', having its upper end recessed and shaped 45 so as to turn inward, the ends of the prongs d projecting from the under side of the button b. This central stem is surrounded by a sliding sleeve C², which is pressed upward by a helical spring C³, resting on the base of the 50 central stem C'. The fabric is placed upon the top of the sleeve C², which is some dis-

tance above the top of the central stem C' and is pressed up by the spring C³, so that when the plunger forces the prongs d through the fabric a, resting on the sleeve C², said sleeve 55 does not descend, but only descends under the pressure of the plunger when the ends of the prongs d are being turned inward by the recessed and shaped upper end of the central stem C' of the anvil. The standard A is also 60 provided with an upwardly-extending arm D, which is curved approximately on a semicircle and on the free end of which the vertical guide D' for the vertically-reciprocating plunger D² is formed. The plunger D² is provided 65 with a recess D³ for receiving the toe D⁴ on the end of a curved lever E, pivoted in a longitudinal slot or recess in the arm D, that end of the lever E opposite the one acting on the plunger D² being connected pivotally by an 70 adjustable connecting-rod E' with the upper end of a lever E², the lower end of which is pivoted to the base-plate A', so that the levers E' and E² form a toggle-lever, the knuckle-joint E³ of which is connected by a connect- 75 ing-rod E⁴ with the upper end of a foot-lever E⁵, pivoted at E⁶ to a bracket E⁷, projecting from the standard A below the arm B on said standard, and which lever E⁵ is provided at its lower end with laterally-extending treadle 80 E⁸. A helical spring E⁹ acts on the toggle-lever to return it to its normal position.

By pressing the treadle E⁸ toward the standard A—that is, toward the left, Fig. 1—the connecting-rod E⁴ is pulled to the right, 85 whereby the left-hand end of the lever D is moved upward and the plunger D² is forced downward, and thereby forces the prongs of the button below it through the fabric and upon the central stem of the anvil, whereby 90 the said prongs are turned inward. Below the plunger a button-supporting plate F is located, which is provided with a recess F', through which the shank and prong of the button can pass, the edges of the said recess 95 being provided with a rabbet F² for receiving the head of the button.

The plunger-guide is extended upward at an inclination as an arm J, on the face of which a button-guide slot I' is formed by two 100 angle-pieces I, secured on the face of this arm and on the front of the plunger-guide. The

lower ends of the pieces I are inclined toward the bottom of the front of the plunger-guide, as shown at I², Figs. 1 and 4.

An escapement-slide K is mounted between the front of the arm J and the plates I to reciprocate transversely and is provided with a pin K', projecting from the rear side, which pin enters a notch K² in the upper end of a trigger-lever K³, pivoted at K⁴ to the back of the vertical part of the arm J, which lever is provided in one edge with a recess K⁵, the ends of which form cams, upon which a bracket-pin L can act, which projects upward from the upper end of the plunger D². The escapement-slide K is provided with a vertical opening M, extending from top to bottom, of a sufficient size for the button-head to pass through it, and in its front the slide K is provided with a slot M', through which the shanks and prongs can pass, this slot being formed on a curved line, so that the lug m is formed on the left-hand side of said slot at the bottom and the lug m' on the right-hand side of said slot at the top, said lugs being displaced vertically, as shown in Fig. 9. As the plunger rises the bracket-pin L rises with it and strikes the upper beveled end of the recess K⁵ in the trigger-lever K³, whereby the escapement-slide K is moved to the right, Fig. 5, which corresponds to a movement to the left of Fig. 9, as Fig. 9 is a front view and Fig. 5 is a back view. By such movement of the escapement-slide to the left, Fig. 9, the lug m passes from under the shank of the button in the slot M', permitting said button to drop to the lower end of the button-guide slot formed between the plates; but at the same time the upper prong m' is moved into the slot I' of the button guide, thus preventing the button next above the one that has just been released from dropping. When the plunger D² descends, the bracket-pin L descends with it and strikes the lower beveled end of the edge of the recess K⁶ in the edge of the lever K³, whereby the escapement-slide K is swung toward the left, Fig. 5, which corresponds to a movement toward the right, Fig. 9, whereby the lowest button in the button-guide above the escapement-slide K is permitted to pass into the slot M'; but it cannot pass through said slot, as the bottom lug m is within the slot I' and arrests the button, keeping it in this position until the plunger again rises. Then this button in the slot M' is released and permitted to drop in the manner just previously described.

The plate F is provided at its ends with the side arms F³, which extend upward to the sides of the plunger-guide D' and are pivoted on pins F⁴, projecting through vertical slots F⁶ in the sides of the guides D', which pins project from cylindrical heads F⁷ on the upper ends of rods F⁸, which project beyond the bottom of the guide D'.

The heads F⁷ can slide vertically in bores F⁹ in guide D' and are pressed upward by

helical springs F¹⁰, surrounding the rods F⁸ within said bores. These springs press the plate F against the lower end of the guide D'. One of the arms F³ of the plate F is provided at its upper end with an upwardly-extending arm G', having its upper end rounded, and this rounded end can impinge on the lower edge of an inclined cam-arm G, projecting upward from one side of the guide D', so that said arm G' can strike it when the plate F is forced upward by its springs F¹⁰.

A trigger-pin G², having a beveled end, is guided in a transverse tubular guide G³ on the outer surface of one arm F³ of the plate F and is pressed outward by a helical spring G⁴.

A pin G⁵ projects laterally from one side of the guide D', and its top is beveled to coact with the beveled end of the trigger-pin G², as shown in Fig. 7.

A U-shaped button-guide frame H is pivoted to the sides of the guide D' in such a manner that its cross-piece H' extends across the guide-slot I' at the lower end thereof and is provided with two downwardly-projecting curved guide-arms H².

A spring H³, acting on an arm H⁴, projecting upward from the frame H, presses the arms H² into position below the guide. When the plunger D² descends to clench a button, it forces down the plate F with it, and as the beveled end of the trigger-pin G² strikes the beveled top of the pin G⁵ the trigger-pin is forced into its guide G³ and does not interfere with the downward movement of the plate F.

When the plate F is forced upward by the action of the springs F¹⁰, the flat top surface of the trigger-pin G² strikes against the flat under side of the pin G⁵, and this throws the plate F outward and away from the button just applied. The pins F⁴, by which the arms F³ are pivoted, are located in a plane some distance from the end of the trigger-pin G², and thus when the plate F and its side arms F³ are forced upward under the action of the spring F¹⁰ the pin G⁵ acts as a fulcrum for the trigger-pin and throws the plate F outward. If the pin G² would be in line with the pivots of the arms F³, then this outward swinging movement could not take place.

By this swinging movement the trigger-pin G² is moved from under the fixed pin G⁵, and they are thus disengaged, and the side arms F³ can move upward under the action of the springs F¹⁰. The upper end of the arm G' on one side arm F³ of the plate F strikes the cam-arm G, and this throws the plate F back into its normal position under the guide D' and plunger D², as shown in Figs. 4, 6, and 7. The plate F thus automatically clears the button that has been applied, thus permitting of pulling the cloth forward into position for receiving the next button without requiring a short reverse movement of the cloth for disengaging the button just applied from the plate F, and so on. As stated, a button slides down the guide-slot I' when the

plunger rises, and this button rests upon the plate F, to which it has been guided from the lower end of the slot I' by the guide-arms H², as shown in Fig. 6. The descending plunger D² 5 presses the guide-arms H² outward, Fig. 4; but when the plunger rises the spring H³ brings said arms back to the normal position against the edge of the plate F, so as to form a continuous guide for the button to said 10 plate F.

A disk N is attached to the upper end of the inclined plate of the arm J, so as to have the same inclination to the vertical as said arm, and this disk is provided with a circular recess 15 N', in which a second disk O can rotate, which disk O rests on the bottom of the recess N', the disk O being provided in its outer surface with a series of radial grooves O', having their inner ends rounded and having a width slightly 20 greater than the diameter of the head of a button, so that the button-heads can pass into said radial grooves, as shown in Fig. 2.

A series of brackets P are secured on the ribs between the recesses O' and to a hopper 25 P', which is provided in its top with an opening Q, through which a quantity of buttons can be placed into the hopper.

As shown in Figs. 1 and 3, a flange R extends partly around the outer edge of the 30 disk N, so as to close the outer ends of the recesses O' of the plate O, thereby preventing the buttons from sliding out of said recesses. This flange extends about half-way around the disk, but is omitted at the remaining 35 half, which remaining half has arranged along the edge of the disk a flange R', which is a distance from the ends of the recess O' and brackets P slightly greater than the diameter of the button-shank, so that 40 the button-shanks can pass into the groove or guide formed by said curved angle-piece R' and the inner ends of said brackets P, as is clearly shown in Fig. 2. The plate O has secured to it a shaft O², carrying a transverse 45 pin O³, which can pass into a transverse groove O⁴ in the lower end of the sleeve O⁵, surrounding the pin O³, so that when the sleeve O⁵ is turned the pin O³, and with it the shaft O², will also be turned. A ratchet-wheel 50 S is held by a screw S', passed through its neck, on the sleeve O⁵ and is engaged by a spring-pawl S² of the rocking arm S³, mounted to rock on the sleeve O⁵ and resting on the neck N³ of the disk N, which rocking arm S³ 55 is connected by a connecting-rod N⁵ with an extension N⁶ of the lever E, so that every time the lever D is operated the ratchet-wheel S is turned the distance of one tooth, as is also the disk O. A quantity of buttons 60 are placed in the hopper P' and by the rotation of the same gradually guided into the several recesses O', in which they slide outward and pass into the button-guide, down which they slide, the lowest button resting 65 upon the escapement-slide K. For each stroke of the plunger downward a button is released, as previously described, and de-

scends until it rests upon the latch-plate F, which is swung out, as described, for every fastened button. Then the button is forced 70 through the fabric and clenched on the anvil, as described, and so on. On top of the stand-ard A a recessed knife T is secured, which is used in conjunction with a blade T', attached to a lever U, and serves for cutting buttons 75 off the fabric when this becomes necessary.

Having described my invention, what I claim as new, and desire to secure by Letters Patent, is—

1. In a button-attaching machine, the combination with a plunger, of a button-guide having its lower end inclined toward the lower end of the plunger, a vertically-sliding button-supporting plate mounted to swing in the direction from the lower end of the guide 85 from the plunger while moving upward, and means for so swinging the plate, substantially as set forth.

2. In a button-attaching machine, the combination with a plunger, of a button-guide 90 having its lower end inclined toward the lower end of the plunger, a button-supporting plate mounted to move vertically and to swing in the direction from the lower end of the guide toward the lower end of the plunger, said 95 plate being in the path of the descending plunger and means for swinging the plate from and toward the plunger during the upward movement of the plate, substantially as set forth.

3. In a button-attaching machine, the combination with a vertical movable plunger and a guide for the same, of a button-guide on the front of the plunger-guide, which button-guide has its lower end inclined toward 105 the lower end of the plunger, a button-supporting plate mounted to slide vertically on the plunger-guide and to swing toward and from the same, means for swinging this supporting-plate toward and from the plunger-guide during the upward movements of said plate, a U-shaped button-guide frame pivoted to the plunger-guide, the cross-piece of said pivoted guide-frame extending across the inclined lower end for the button-guide, 115 a spring pressing said cross-piece on said inclined part at the lower end of the button-guide, and downwardly-projecting arms on the cross-piece of the pivoted guide-frame, substantially as set forth.

4. In a button-attaching machine, the combination with a plunger and a button-supporting plate having upwardly-projecting arms by which it is pivoted and mounted to move vertically, the supporting-plate being 125 below the plunger, of a spring-trigger on one of the arms of said plate, a fixed pin for engagement with said trigger, a fixed cam in the path of one arm of said button-supporting plate and located above said arm, substantially as set forth.

5. In a button-attaching machine, the combination with a plunger, of a button-supporting plate below the plunger, and having up-

wardly-extending arms, vertically-movable guides to which said arms are pivoted, a spring-trigger projecting beyond the vertical plane through the pivots of said arms and having its upper surface flat and its lower surface beveled, and a fixed pin having its under side flat and its upper side beveled, substantially as set forth.

6. In a button-attaching machine, the combination with a plunger and button guide, of a button-escapement slide mounted to move transversely in the guide, a pivoted lever having cam edges and having its upper end disengaged with the slide, and an arm projecting upward from the plunger and engaging the cam edges of said lever, substantially as set forth.

7. In a button-attaching machine, the combination with a plunger and a plunger-guide,

of guides mounted to move vertically in said plunger-guide, a spring for pressing said guides upward, a button-supporting plate below the plunger-guide and in the path of the descending plunger, upwardly-extending arms on said plate, pivots by means of which said arms are pivoted to the movable guides in the plunger-guide, and means for throwing said button-supporting plate from and toward the plunger during the upward movement of said plate, substantially as set forth. 30

Signed at New York city, in the county of New York and State of New York, this 14th day of January, A. D. 1901.
